UNITED STATES PATENT OFFICE.

JOHN S. SALVA, OF LATONIA, KENTUCKY, ASSIGNOR TO THE SALVA CARBURETER COMPANY, OF COVINGTON, KENTUCKY, A CORPORATION OF KENTUCKY.

CARBURETOR.

Application filed February 8, 1926. Serial No. 86,825.

One feature of carburetor performance that is not recognized by automotive engineers generally is that the fuel supplied to an internal combustion engine by means of a carburetor is not always vaporized in the carburetor. On the contrary, with the majority of carburetors heretofore in use, the fuel is drawn into the air stream by the suction of the engine piston, and is carried with the air into the cylinder in a liquid state. Sometimes, but not always, the fuel is supported by the air stream in the form of minute drops suspended therein. The generally accepted idea that a carburetor is a vaporizing device may easily be shown to be a fallacy by inserting a short length of clear glass tubing between the carburetor and the branched portion of the engine manifold. This will show that the fuel passes to the engine cylinder in liquid form, usually swirling about and enveloping the air stream, clinging to the inner surface of the inlet manifold.

Those carburetor engineers who have recognized this peculiarity of the air-fuel mixture when passing from the carburetor to the engine cylinder, have devised various methods for the purpose of securing a more intimate mixture of the fuel with the air while the fuel is passing through the carburetor, and of maintaining the mixture intact while it is on its way from the carburetor to the engine cylinder. These methods have included air-bleeders of various designs, and generally of such construction that a small stream of air will meet the fuel as it passes from the float chamber of the carburetor on its way to the point where it meets the main air stream in the co-called mixing chamber of the carburetor. This method has proven efficacious to a certain degree and is employed in a number of well-known makes of carburetor. In fact, the air-bleeder into the fuel stream was the subject of an extended litigation based on the presumably fundamental patent to G. V. Ahara, No. 684,662. But in all carburetors employing the basic principle of the Ahara patent, and modifications thereof, the air meets the fuel after the latter has entered the fuel passage on its way from the float chamber to the mixing chamber. The Ahara method, while it shows a decided improvement in carburetor

performance as compared to carburetors not so fitted, does not fully meet the requirement of forming an intimate mixture of the fuel with air before the mixture leaves the carburetor.

The advantage to be gained by forming an intimate mixture of the fuel with the air may be counteracted by the refrigerating action due to the vaporization of the fuel. This cooling effect tends to condense the fuel that may have been vaporized, overcoming the advantage gained thereby. The obvious method of counteracting this tendency is to heat the fuel or the fuel and air mixture. A number of methods of heating the fuel or the air or the fuel-air mixture have been employed heretofore. These heating means include passing the air supply to the carburetor through a "stove" surrounding the exhaust pipe of the engine, jacketing the air passages with hot exhaust gases or with hot water from the engine jacket, and the application of heat by means of electric current from a storage battery or other source. But many of these methods have failed of their purpose, the maintaining of the fuel in the form of a vapor after it leaves the carburetor and until it enters the engine cylinder. The efficient application of heating means to the fuel is essential when operating an engine with the fuels of a specific gravity below that of commercial gasoline, and when the engine is operated upon the Otto cycle.

The main object of this invention is to form an intimate mixture of the fuel with a small proportion of initial air, the mixing of the two taking place at the point where the fuel leaves the float chamber and enters the passage through which it is about to pass from the float chamber to the mixing chamber of a carburetor. Another object of my invention is to provide a means of heating the mixture of fuel and initial air as it is passing from the float chamber to the mixing chamber. Another object of my invention is to provide a passage of appreciable length within a small space, in which passage the mixture of fuel and initial air may be passed over a surface of sufficient area to absorb the requisite quantity of heat. With these and other objects not specifically mentioned in view, my invention consists in certain combinations,

constructions and parts which will be hereinafter described and specifically pointed out in the claims hereunto appended.

In the accompanying drawings which form a part of this specification;

Fig. 1 is a sectional elevation along the line 1—1 of Fig. 2.

Fig. 2 is a sectional elevation along the line 2—2 of Fig. 1.

Fig. 3 is a perspective of the heating drum with the outer shell thereof partially broken away to show the helical groove forming the helical passage for the mixture of fuel and initial air. This figure shows the heater considerably enlarged.

Fig. 4 is an enlarged fragmentary section taken along the same plane as Fig. 1. It is designed to show more clearly than in the smaller scale of Fig. 1, the relative positions of the parts and the paths of the air and the fuel.

Fig. 5 is a development of the heating element 40, showing it as it appears before it is wrapped around the heating drum.

In carrying this invention into effect, there is provided a main carburetor body with a Venturi tube therein provided, the main body having a downwardly extending tubular portion or "standpipe" provided with a central passage therein, a bowl surrounding the standpipe, and a float in the bowl having a float valve operatively connected therewith for the purpose of maintaining an approximately constant level of fuel in the bowl.

The space within the bowl is customarily termed the "float chamber" and will be so referred to hereinafter. Within the standpipe and extending thereto from the mixing chamber is a valve adapted to adjust the area of the passage from the float chamber to the mixing chamber and customarily termed the "needle valve." The needle valve in this instance is provided with a passage throughout the entire length thereof. It is

through this passage that the initial air enters the float chamber at a point below the surface of the fuel therein. Surrounding the standpipe, and separated therefrom by a cylinder of refractive material, is a heating drum provided with a helical passage therein adapted for the passage of the initial fuel-air mixture on its way from the float chamber to the mixing chamber. Surrounding the heating drum is a layer of refractive material, preferably ribbon mica, and over this is a heating element of chrome-nickel or similar wire. Surrounding the heating element is an enclosing cup-like cover of refractive material, preferably lava.

One end of the heating element is grounded on the body of the carburetor, and the other end of the element is connected to a binding post.

In the preferred construction, as shown in the accompanying drawings, 6 is the body

of the carburetor, which follows the conventional form customarily employed for engines of low-priced automobiles. The body 6 is provided with a main air passage of the double-cone type or Venturi form 7 containing the customary choke valve 8 and the throttle valve 9. The central portion of this passage is customarily referred to as the mixing chamber. The downwardly extending standpipe 10, surrounding which is the bowl 11 providing the float chamber 12. The usual float 13 is hinged at 14 and controls the float valve 15 for the admission of liquid fuel to float chamber 12. The bowl is held in place by means of the screw 16, which is provided with a drain plug 17. The parts above enumerated are such as are generally to be found in carburetors of conventional design and are the fundamental parts to which my improvements are applied.

Passing downward through the center of the mixing chamber and extending into float chamber at the center of the standpipe is the tubular needle valve 18. The needle valve is fitted with the double-ended control lever 19, riveted thereto. Near the lower end of the needle valve is a conical valve seat 20. The needle valve is provided with a passage 21 drilled through the entire length thereof. Near the top of the valve is provided a cross passage 22, the area of which is controlled by the screw valve 23, by means of which the entrance from 22 to 21 may be partially or wholly closed. The needle valve is surrounded with a lock nut 24 having a tapered thread thereon, and provided with saw slots 24', for purpose of clamping the needle and maintaining it in the position to which it has been adjusted. Near the lower end of the standpipe is a hollow screw 25 provided with the passage 26. The bore of the screw is slightly larger than the reduced end 18' of the needle valve, and a passage between the two is thereby provided.

Surrounding the standpipe 10 and separated therefrom by the cylinder 32 is the heating drum consisting of the body 27, provided with the helical groove 28 in the form of a screw thread cut therein. Surrounding the body is the tubular cover 29 which is shrunk into place and the ends 30 thereof spun over the ends of the body. The construction of the heating drum is best shown in the enlarged perspective Fig. 3. As a whole, the drum, as constructed, forms an easily and cheaply manufactured substitute for a heating coil, and one which is well adapted to the application of the heating element. Surrounding the heater drum is an enclosure of refractory material. This enclosure or heater case is comprised of a body 31 having a central core 32, a top 33 and a flanged extension 34. The body is provided with a female thread 34' into which is screwed the cover 35 by means of the male 130

thread 35' thereon. Within the case is the heater drum, which is slipped over the core 32. Above and below the heating drum are the washers 36-36 (Fig. 4) which close the ends of the drum. Since the flanges 30 do not entirely cover the ends of the helical groove, a space is provided forming the passages 30'-30' between ends of the heater drum and the washers.

10 Centrally of the standpipe there is provided a bore 10' closely fitting the main stem of the needle valve so that there is no passage between them at this point. The passage 10' is enlarged at 10" by counterboring, and again at 10", forming passages in each instance between the needle valve and the inner wall of the standpipe. Ports 37-37 are provided by drilling through the standpipe into the counterbore 10" and corresponding ports 38-38 by drilling through the standpipe into the counterbore 10". Ports 37'-37', to register with ports 37-37, are drilled through the core 32, and similar ports 38'-38' are drilled through 25 32 to register with ports 38-38. Ports 37' and 38' provide communication with the passages 30', 30'.

Surrounding the heater drum cover is a layer 39 of ribbon mica, and about this 30 layer is wrapped the heating element 40, shown in flattened form in Fig. 5. The end 41 of the element is formed into an eye 41 for convenience in attaching it to the binding post 43, while the end 42 is bent at 35 a right angle. As shown in Fig. 2, the end 42 is clamped against the body 6, being laid in a groove suitably provided in the top of the heater case. The actual position of the end 42 is about 150° of arc from the position shown, this position being chosen for the purpose of illustration. A conventional 40 battery is shown at 45, one terminal of the battery being attached to binding post 43, and the other terminal grounded on the body 45 6. It is obvious that a switch and a rheostat may be inserted in the battery leads without departing from the purpose of the invention. Insulation of the binding post from the body is secured by insulation 44. 50 The heating element may be packed about with fibrous packing 40', using asbestos, powdered mica or similar refractive material.

In Fig. 1, just to the right of throttle 9, 55 is a small ball valve 46 for the admission of air to the fuel-air mixture to aid in maintaining the economy of fuel when operating at or near full load. The use of such a valve is not new in the art and is 60 illustrated as showing a completed practical device.

The operation of the invention consists of the ordinary adjustments as customary with carburetors not fitted with the improve-

ments shown, and in addition the adjustment of the initial air inlet valve 23, and the heating of the drum 27. With gasoline, the current is turned into the heating element just before starting the engine, and may be turned off soon after the engine is 70 started, when the atmosphere is comparatively warm. When using the heavier fuels such as kerosene, the current is allowed to flow through the heating element continuously. When the engine is running, air for 75 the initial mixture enters at 22, passes downwardly through passage 21 as indicated by the arrows (Fig. 4) enters the fuel at the lower end of 18 whence it passes with the fuel through the passage 26 into counterbore 10", through ports 38 and 38' to space 30' through groove 28 to the upper space 30', through ports 37' and 37 to counterbore 10", whence it passes to mixing chamber 80 7. The passage of the mixture of initial air and fuel through this long passage thoroughly aerates the fuel, and the heat absorbed while passing through 28 transforms the fuel into vapor and raises it to a temperature that will effectually prevent 90 condensation.

I claim:—

1. In a carburetor comprising a mixing chamber, a float chamber, a standpipe central of the float chamber, a tubular needle valve in the standpipe and central thereof, a heater drum surrounding the standpipe, a helical passage provided in the drum, and passages in the standpipe so provided that they communicate with the passage in the 95 drum in such manner that the mixture is compelled to pass from the float chamber through the helical passage on its way to the mixing chamber.

2. In a carburetor comprising a mixing 100 chamber, a float chamber, a standpipe central of the float chamber, a drum surrounding the standpipe, a helical passage in the drum, passages in the standpipe providing communication from the float chamber to 105 the helical passage, and other passages in the standpipe providing communication from the helical passage to the mixing chamber.

3. In a carburetor comprising a mixing 110 chamber, a float chamber, a standpipe central of the float chamber, a drum surrounding the standpipe, a helical passage in the drum, passages in the standpipe providing communication from the float chamber to 115 the helical passage, other passages in the standpipe providing communication from the helical passage to the mixing chamber, and an electrical heating element surrounding the drum.

In witness whereof, I have hereunto affixed my signature.

JOHN S. SALVA.
